**MACHINE FOR REMOVING THE BALLAST FROM
BENEATH RAILWAY TRACK SLEEPERS**

Jack C. Stein, 408½ E. Broadway, Missoula, Mont.

Filed Mar. 14, 1958, Ser. No. 721,574

7 Claims. (Cl. 37—104)

This invention relates to railroad ballasting machines and, more specifically, the instant invention pertains to the provision of a machine especially designed for removing foul ballast from between and under the ties or sleepers supporting a railroad track.

An object of this invention is to provide a machine for removing the ballast from between and below railroad track ties or sleepers together with means for effecting the removal of the ballast to a predetermined level.

A further object of this invention is to provide a machine of the type generally described above, which will effectively remove foul ballast from beneath the ties of a railroad track without requiring dismantling or disconnection of the rails from the ties.

It is still a further object of this invention to provide a machine for removing foul ballast from below railroad ties wherein the ties and connected rails pass over the machine together with means for adjusting the depth of the cutting blades for the removal of the ballast to a predetermined level independent of the weight of the ties and rails passing thereover.

It is another object of this invention to provide a machine of the type generally described supra to effect the filling in of low spots in the ballast for a railroad track.

A still further object of this invention is to provide a machine of the type described above, the machine being non-complex in construction and assembly, inexpensive to manufacture, and durable in use.

Other and further objects and advantages of the present invention will become more evident from a consideration of the following specification when read in conjunction with the annexed drawings, in which:

Figure 1 is a schematic top plan view of the machine constructed in accordance with the present invention and illustrating its mode of attachment to a railroad flat car of conventional design;

Figure 2 is a detail top plan view of the machine illustrated in Figure 1;

Figure 3 is a side elevational view of the device or machine illustrated in Figure 2;

Figure 4 is an end elevational view of the machine, Figure 4 being taken substantially on the vertical plane of line 4—4 of Figure 3, looking in the direction of the arrows;

Figure 5 is a fragmentary detail cross-sectional view taken substantially on the inclined plane of line 5—5 of Figure 2, looking in the direction of the arrows;

Figure 6 is an enlarged fragmentary detail cross-sectional view taken substantially on the vertical plane of line 6—6 of Figure 3, looking in the direction of the arrows;

Figure 7 is a side elevational view of the machine, wherein the several ballast removing blades have been changed in their positions to extend transversely across the machine in a substantially straight line;

Figure 8 is a top plan view of the machine illustrated in Figure 7;

2

Figure 9 illustrates a second embodiment of a ground engaging skid for the machine;

Figure 10 illustrates a third embodiment of a ground engaging skid for the machine; and,

Figure 11 illustrates a fourth embodiment of a ground engaging skid for the machine.

Referring now more specifically to the drawings, reference numeral 20 designates, in general, a machine especially designed in accordance with the teachings of this invention for removing foul ballast from beneath and below railroad ties and track. As is seen in Figures 1—6, inclusive, the machine 20 comprises an open substantially rectangular frame which includes a pair of elongated laterally spaced, substantially parallel and confronting side frame members 22, 24 rigidly secured together adjacent their respective upper ends by means of a plurality of longitudinally spaced and substantially parallel cross-braces 26, 28, 30, 32 and 34. The side frame members 22, 24 are further reinforced by a substantially V-shaped truss 36 the apex 38 of which is rigidly secured, as by welding, to the cross-brace 28. The arms 40, 42 of the truss 36 diverge towards the forward end of the machine 20 and are rigidly connected to the cross-brace 30 and to one of the ends of a pair of converging struts 44, 46, respectively. As is clearly seen in Figure 2, the other end of the strut 44 is rigidly connected to the strut 46 adjacent one of its ends, and the strut 46 crosses the cross-brace 32 proximate its other end which is rigidly secured to the side frame member 22. Conventional means are also provided to rigidly connect the strut 46 to the cross-brace 32. A third strut 47 has one of its ends fixedly secured to the strut 46 in longitudinal alignment with the strut 44, and the strut 47 traverses the cross-brace 32 proximate its other end, the latter being rigidly secured to the side frame member 24. As before, conventional means are employed to rigidly connect the strut 47 to the cross-brace 32 at the point of traverse. A substantially V-shaped truss 48 is also provided, the truss 48 having forwardly extending converging arms 49, 50 rigidly secured to the struts 46, 47 and its apex 51 fixedly secured or connected to the cross-brace 34.

As is seen in the figures, the side frame members 22, 24 are of identical construction and each is formed with an arcuate forward end 53, which as it curves rearwardly, 45 makes junction with a rising curved upper end 52 of the side frame members 22, 24. This curved upper end 52 extends throughout the major lengths of the side frame members 22, 24 and is struck on a radius greater than the radius of the forward end 53. The rising curvature 50 of the upper end 52 passes substantially the center point thereof, and substantially adjacent thereto the curvature is reversed to merge with the arcuately shaped rear end 54 struck substantially on the same radius as the radius of the forward end 53.

Each of the side frame members 22, 24 are formed with a pair of arcuately shaped intersecting cutout portions 56, 58 around the rear marginal edges of which are provided a series of transversely extending openings 60, 62, respectively.

Referring now more specifically to Figures 1 and 6, it is seen that the forward and rearward ends of the side frame members 22, 24 have secured thereto skid elements 64. Each of the skid elements 64 includes an elongated semi-circular portion including ground engaging side arms 66, 68 and a centrally positioned bight 70 from which project a plurality of longitudinally spaced pairs of confronting lugs 72, 74 which embrace opposite sides of the lower end of the side frame members 22, 24 and which are releasably secured thereto by means of bolts 76 and nuts 78.

To the upper ends of the side frame members 22, 24

are secured a pair of identically constructed tie or sleeper slides 80, respectively, each slide having an inverted substantially V-shaped configuration including a pair of laterally spaced, substantially parallel and confronting side arms 82, 84 which embrace opposite sides of the side frame members 22, 24 and are secured thereto by a plurality of screws 86 and nuts 88. The bight portion 90 of the slides 80 culminate in linearly extending pointed edges 92 (see Figure 6).

To the cross-brace 26 are rigidly secured one of the ends 94, 96 of a pair of angle brackets 98, 100, respectively, from which depend the other arcuately shaped end members 102, 104.

Spaced forwardly from the brackets 98, 100 and converging rearwardly from the side frame members 22, 24 are a second pair of arcuate brackets 106, 108. A third pair of downwardly inclined, rearwardly converging, arcuate brackets 110, 112 depend from the struts 44, 46; and a fourth pair of similar rearwardly converging brackets 114, 116 depend from the side frame members 22, 24; and a fifth pair of similar rearwardly converging, downwardly inclined brackets 118, 120 depend from the arms 49, 50, respectively, of the truss 48. A sixth pair of brackets are generally designated at 122, 124 each of which include (see Figure 5) an elongated substantially rectangular leg portion 126 having a plurality of longitudinally spaced adjusting apertures 128 extending transversely therethrough to serve a function to be described. The inner ends of the leg portions 126 are rigidly secured, by conventional means, to the rear ends 54 of the side frame members 22, 24. The outer ends of the brackets 122, 124 terminate in depending arcuately shaped sections 130. Substantially intermediate the side frame members 22, 24 and diverging outwardly and rearwardly therefrom are a pair, respectively, of laterally extending arcuate brackets 132, 134. A seventh pair of arcuately shaped brackets 136, 138 depend from the struts 46, 47, respectively, adjacent the forward ends thereof, and to the forward ends 51 of the side frame members 22, 24 are secured, respectively, an eighth pair of brackets (see Figures 3 and 8) 140, 142 each of which have a substantially rectangular portion 144, 146 projecting forwardly thereof and a laterally offset depending arcuate section 148, 150.

From the side frame members 22, 24 adjacent their respective front ends laterally project a pair of diverging plates 152, 154, respectively, the plates terminating in a pair of substantially upright forwardly projecting flanges 156, 158.

An elongated rod 160 extends transversely across the machine 20 at its forward end and the outer ends thereof are connected by the pairs of links 162, 164 and 166, 168. On the remote ends of the rod 160 are pivotally connected between the pairs of links 162, 164 and 166, 168 the inner ends of a pair of braces 170, 172, the outer ends of which converge for rigid connection at 174, 176 with a draw bar 178 intermediate the ends of the latter. The inner end of the draw bar 178 is pivotally connected at 180 on the rod 160 at substantially the midpoint thereof. Rigidly connected to the rod 160 on opposite sides of the inner end 180 of the draw bar 178 are a pair of support members 182, 184 on which are rotatably journaled a pair of cylindrical rail guides or rollers 186, 188, respectively, the axes of the latter being substantially vertical. As is clearly seen in Figure 4, the upper ends of the rollers 186, 188 are formed with radial flanges 190, 192, respectively.

Referring now more specifically to Figures 2 and 3, reference numerals 194, 196 denote a pair of arcuately shaped plows at one side of the machine 20 and numerals 198, 200 designate a similar pair of plows on the other side thereof. A pair of arcuately shaped scarifying blades are indicated at 202, 204. Each of the plows and blades are formed with three series of radially spaced transversely extending apertures 206, 208, and 210 (see Figure

4) to receive bolts 212 therethrough for connection to the above described arcuate brackets in arrangements to be referred to below, and each blade and plow are formed with a pair of spaced confronting apertured lugs 214, 216 to serve functions also to be related.

As is seen in Figure 1, the outer end of the draw bar 178 is pivotally connected at 218 to a plate 220 to which is connected a pair of braces 222, 224, the other ends of the latter diverging away from each other and are pivotally connected at 226, 228 to a pair of plates 230, 232 rigidly connected to opposite sides of a flat car 234 adjacent an end thereof.

To utilize the above described machine 20, and assuming that all of the above described elements forming component parts thereof are in the full line position illustrated in the above referred to figures, the rod 160, braces 170, 172 and draw bar 178 are disconnected therefrom. Thereafter, a section of the track 236 including the rails 238, 240 and the ties 242 to which they are connected is elevated and the machine 20 is then slid laterally thereunder. Conventional jacks are employed for effecting the elevation of the track 236. The elevating jacks (not shown) are then depressed to permit the ties 242 to engage and ride on the pointed edge 92 of the slides 80. The rod 160, braces 170, 172 and draw bar 178 are now reconnected to the machine 20. The plows 194, 196, 198, 200 and the scarifying blades 202, 204 are then adjusted to their desired cutting depths after which the draw bar 178 is connected to the flat car 234 in the manner as described above.

The flat car 234 is, of course, connected with locomotive means which when activated causes the machine 20 to move in a straight lined direction parallel to the rails 238, 240. It should be here noted that the rollers 186, 188 have been previously adjusted to bear against the inner sides of the rails 238, 240 with the flanges 190, 192 engaging thereover. With the blades 194, 196, 198 and 200 and the scarifying blades 202, 204 arranged in the V-shaped formation illustrated in full lines in Figure 2, the ballast will be spewed to each side of the track 236. In making the adjustments of the blades and plows it is important that the depth of the desired cut will not require that the lower edges of the plows and blades project downwardly below the ground engaging side arms 66, 68 of the skid elements 64. Thus, the weight of the track 236 and the attached ties 242 are borne entirely by the skid elements 64. This prevents the machine 20 from veering from side to side beneath the track 236 due to extreme side pressures on the plows and blades.

The machine 20 also finds utility in grading banked curves. In all heretofore known devices of this general type, the grading plows supported at least partially, the weight of the tracks and ties or sleepers. Thus, as the device was towed across a curve, the plows at the lower side thereof were prone to take a deeper cut than the plows at the upper side. This resulted in an undesirable change in the grade of the curve. With the machine 20 constructed in accordance with this invention, this objectionable feature is entirely eliminated since the weight of the ties and track is supported entirely upon the skids.

In the embodiment of this invention illustrated in Figures 1 to 4, inclusive, the machine 20 has been illustrated as being equipped with scarifier blades 202, 204. These may be replaced, of course, with other plows, similar to the plows 194, 196. The scarifier blades 202, 204 are employed when it is desired to loosen up and to remove the hard material lying below the track ballast wherein it is desired to lower the elevation of the tracks. This is of importance in connection with the establishment of a sufficient clearance in tunnels, bridges, and other similar structures. To utilize the machine 20 under these conditions, the scarifiers are connected thereto in the manner illustrated and described and a pass is made beneath the track. Thereafter, the scarifying blades 202, 204 are removed and a third pair of plows are substituted there-

for to effect removal of the scarified material upon the second pass of the machine 20 under the track 236.

The construction of the machine is such as to permit the arrangement of the plows to be disposed at an acute angle with respect to the longitudinal axis of the track 236 for discharge of the ballast to either side thereof. To this end it should be noted that the brackets 130, 104 and 132 are aligned with one another. The brackets 108, 112, and 136 are also aligned with one another. Brackets 116, 120 and 148 are also disposed in longitudinal alignment with each other. To discharge material to the right of the track 236, the plows 194, 196 and scarifying blade 202 are disconnected from the brackets illustrated as supporting the same in Figure 2 and these plows and blades are then rotated substantially ninety degrees and their respective inner ends are overlapped (see Figure 2) for connection with the brackets 104, 112, and 120. The outer ends of the blade 202, plows 194 and 196 are now fixedly secured to the brackets 32, 136 and 148, respectively.

The other bracket 130 and brackets 102 and 134 are aligned as are the brackets 106, 110 and 138. The brackets 114, 120 and 150 are also disposed in alignment one with another. These aligned brackets make it possible for the blade 204 and plows 198, 200 to be rotated in a counterclockwise direction and overlapped, as before, in order to effect discharge of the ballast material to the other side of the track 236.

Optionally, the blades and the plows may be connected to the machine 20 in a direction extending substantially perpendicular to the longitudinal axis of the track 236. To obtain this arrangement, the blades and plows are disconnected from the brackets referred to above and are disposed in overlapped condition relative to each other. Thereafter, the lugs 214, 216 fixedly secured thereto, may be connected by bolts to any one of the apertures 60, 62 or apertures 128.

This last feature of applicant's invention is clearly illustrated in Figures 7 and 8 of the drawings.

Figures 9 to 11, inclusive, illustrate other types of skid elements which may be employed in the practice of this invention. In Figure 9 the skid element is assigned reference numeral 300 and is seen to comprise an elongated inverted substantially V-shaped member having side arms 302, 304 which converge towards a bight portion 306. Integrally formed with the bight portion 306 and projecting away therefrom are a pair of longitudinally extending flanges 308, 310 which are secured to the lower ends of the side walls 22 or 24 by means of bolts 312 and nuts 314.

In Figure 10 the skid element is designated, in general, by reference numeral 400 and is seen to comprise an inverted substantially U-shaped member including a pair of laterally spaced longitudinally extending, parallel and confronting side arms 402, 404 connected at one of their adjacent pairs of ends by a bight 406. As before, a pair of longitudinally extending flanges 408, 410 are rigidly secured to the bight 406 and project away therefrom for connection against opposite sides of the side frame members 22, 24 by means of bolts 412 and nuts 414.

In Figure 11 the skid element is assigned reference numeral 500 and is essentially T-shaped in configuration including a ground engaging stem 502 to which is rigidly connected a cross head 504 from which project a pair of flanges 506, 508 for engagement on opposite sides of either of the side frame members 22 or 24, the flanges being connected thereto by means of bolts 510 and nuts 512.

Having described and illustrated one embodiment of this invention in detail, it is to be understood that the same is offered merely by way of example, and that the present invention is to be limited only by the scope of the appended claims.

What is claimed is:

1. A machine for removing ballast from a railroad track bed, said machine comprising a substantially open

rectangular frame including a pair of elongated substantially upright side frame members, a plurality of longitudinally spaced cross-braces extending transversely between said side frame members and having their respective ends fixedly secured to the adjacent one of said side frame members, a plurality of reinforcing struts and trusses rigidly secured to said side frame members and to said cross-braces, a plurality of arcuately shaped downwardly extending brackets secured to said side frame members, said trusses and struts, a plurality of arcuately shaped plows, means detachably connecting said plows to said arcuate brackets, a ground engaging skid for each of said side frame members, a slide fixedly secured to the upper ends of each of said side frame members, and draw bar means fixedly connected to said side frame members for connection with a source of locomotive power.

2. A machine for removing ballast from a railroad track bed as defined in claim 1, wherein said skids have a semi-circular transverse configuration.

3. A machine for removing ballast from a railroad track bed as defined in claim 1, wherein said slides each have an inverted substantially V-shaped configuration.

4. A machine for removing ballast from a railroad track bed as defined in claim 1, wherein said skids each have an inverted V-shaped transverse configuration.

5. A machine for removing ballast from a railroad track bed as defined in claim 1, wherein said skids have an inverted substantially U-shaped transverse configuration.

6. A machine for removing ballast from a railroad track bed as defined in claim 1, wherein said skid has a substantially T-shaped transverse configuration.

7. A machine for removing ballast from a railroad track bed, said machine comprising a substantially open rectangular frame including a pair of elongated laterally spaced and substantially parallel side frame members, a plurality of longitudinally spaced and substantially parallel cross-braces extending between said side frame members and rigidly secured thereto, a plurality of reinforcing struts and a truss rigidly secured to said cross-braces and to said side frame members, a first and second series of substantially arcuate brackets depending from said side frame members and one of said cross-braces, said arcuate brackets of one of said series being disposed in a common curvilinear plane and said arcuate brackets of said second series being disposed in a common curvilinear plane with said first and second curvilinear planes intersecting at substantially right angles with respect to one another, a third and fourth series of substantially arcuate brackets depending from said side frame members and said struts, said arcuate brackets of said third series being disposed in a common curvilinear plane and said arcuate brackets of said fourth series being disposed in a common curvilinear plane, said last named curvilinear planes intersecting at right angles with respect to each other, a fifth and sixth series of arcuate brackets depending from said side frame members and said truss, said arcuate brackets of said fifth series being disposed in a common curvilinear plane and said brackets of said sixth series being disposed in a common curvilinear plane, said last named curvilinear planes intersecting at right angles with respect to each other, said side frame members having arcuately shaped cutout portions extending transversely therethrough in longitudinally spaced relation relative to each other, a plurality of arcuately shaped plows, means for connecting said plows to any selected two of said brackets of any of said series with an end of each of said plows extending through said arcuate cutouts on one, the other, or both sides of said side frame members, each of said side frame members having an arcuately shaped upper end, a substantially V-shaped tie supporting slide mounted on the upper ends of each of said side frame members, said slides following the configuration of said upper ends of said side frame members, a rod extending transversely of said side frame members adjacent an end thereof and

50

55

60

65

70

75

being rigidly secured thereto, a drawbar pivotally mounted adjacent one of its ends on said rod, and a pair of railroad track engaging rollers rigidly secured to said rod.
